CLAIM

The ornamental design for an upholstered seat, substantially as shown and described.

DESCRIPTION

FIG. 1 is a front perspective view of a seat embodying the present invention in the form of an easy chair;

FIG. 2 is a perspective view looking from the right side of FIG. 1, the left side being the same as the right side;

FIG. 3 is a rear view of said chair;

FIG. 4 is a front perspective view of a seat embodying the present invention in the form of a love seat;

FIG. 5 is a perspective view of the love seat of FIG. 4 looking from the right of FIG. 4, the left side being the same as the right side;

FIG. 6 is a rear perspective view of said love seat;

FIG. 7 is a front perspective view of a seat embodying my design in the form of a sofa;

FIG. 8 is a perspective view looking from the right side of FIG. 7, the left side being the same as the right side; and

FIG. 9 is a rear perspective view of the sofa of FIGS. 7 and 8.

FIG. 1.

FIG. 2.

FIG. 3.

FIG. 5.

FIG. 4.

FIG. 6.

FIG. 7.FIG. 9.*FIG. 8.
